(57) **CLAIM**

The ornamental design for a fastener for a conveyor belt, as
shown and described.

DESCRIPTION

FIG. 1 is a front perspective view of a fastener for a
conveyor belt, showing my new design;
FIG. 2 is a right side elevational view thereof;
FIG. 3 is a left side elevational view thereof;
FIG. 4 is a top plan view thereof;
FIG. 5 is a bottom plan view thereof;
FIG. 6 is a front elevational view thereof;
FIG. 7 is a rear elevational view thereof; and,
FIG. 8 is an environmental rear perspective view of FIG. 1
showing the fastener for a conveyor belt interconnected with
another fastener by a wire.

The broken lines showing of the second fastener and wire,
in FIG. 8, illustrates the environment of the claimed design
and forms no part thereof. The remaining broken lines in the
drawings illustrate portions of a fastener for a conveyor belt
and form no part of the claimed design. The dot-dash-dot
broken lines in these drawings define the bounds of the
claimed design and form no part thereof.

1 Claim, 6 Drawing Sheets
